CIRCULATION EQUALIZER FOR FURNACE
FLUES

James Z. Anderson, Brookfield, Ill.

Application March 20, 1933, Serial No. 661,859

9 Claims. (Cl. 126—105)

This invention relates generally to hot air furnaces, and particularly to means for automatically evacuating the mother flue of cold air when starting up a furnace and increasing the amount 5 of warm air conveyed by the mother flue when the furnace is in full operation.

I have discovered that cold air present in the mother flue of a hot air furnace before the furnace has been fired and while the furnace is heating up offers considerable resistance to the passage of warm air from the furnace to the room to be heated. Before hot air from the furnace can reach the room it must either displace this cold air or raise the temperature thereof, and where 10 the mother flue opens into a closed room or space, the cold air in the room must be displaced or raised in temperature before any substantial rise in the temperature in the room can take place. Heretofore expensive mechanical means has been suggested for evacuating the mother flue and the cold room of cold air to provide quickly for a free 15 flow of hot air from the furnace and none of these means have been automatic in action, and required skillful operation to secure satisfactory 20 results. My invention supplies an entirely automatic means dependent for its action on the state 25 of the air in the mother flue and the operating condition of the furnace, and the costs of manufacturing and installing of my invention are so small as to present no obstacle to its use by every 30 owner of a hot air furnace.

In the drawings:

Figure 1 is a top plan view of a hot air furnace and its mother flue showing an embodiment of 35 my invention applied thereto.

Figure 2 is a transverse vertical sectional view taken through Figure 1 approximately on the line 2—2.

Figure 3 is a transverse vertical sectional view 40 taken approximately on the line 3—3 of Figure 2.

Figure 4 is a horizontal sectional view taken on the line 4—4 of Figure 2.

Referring now to Figure 2 of the drawings, the 45 numeral 5 designates a hot air furnace including the customary firepot 6. Spacedly enclosing the furnace 5 is the usual casing forming the air heating chamber and having the dome 7a. The cold air to be heated is admitted to the chamber by an intake 8. Before proceeding further, I desire to call attention to the fact that any suitable 50 number of mother flues 10 may lead from the dome 7a of the casing 7. It will be understood that the cold air entering the chamber through the intake 8 will be heated by contact with the furnace and will rise in the chamber and pass out

through the outlet neck 9 to which is connected the mother flue 10. This flue 10 includes the usual horizontal portion which extends radially outwardly from the dome 7a to convey the hot air to a room or other enclosure to be heated.

In the case of an ordinary hot air furnace it is in the horizontal portion of the mother flue 10 that the cold air collects and opposes the passage of hot air to the room to be heated. As the furnace is first fired and the temperature of the air 10 in the air heating chamber of the furnace gradually rises, it exerts a gradually increasing outward pressure on the column of cold air in the said horizontal portion so that this column of cold air begins to move outwardly, all the time resisting the passage of warm air through the mother flue. Since the column of cold air must go somewhere, it ordinarily goes into the already cold room, and there being no escape for the cold air in the room thus augmented, the air in the room 15 will not become warm until its temperature has been slowly raised by contact with such hot air as finally enters the room through the mother flue 20 10.

Taking advantage of the natural tendency of 25 cold air to sink to lower levels, I tap the said horizontal portion at a radially outward point by connecting to one side of the lower part thereof one end of a pipe or flue 11 of relatively 30 small diameter, into which the cold air flows downwardly of itself and in its downward flow in the pipe is assisted by the movement of the mentioned column of cold air under the impetus of the developing column of hot air behind the column of cold air.

The auxiliary flue, which may also be referred to as an equalizing flue lies along and preferably in contact with the side of the lower part of said horizontal portion of the mother flue as indicated by the numeral 16. The elbow connecting the outer end of the auxiliary flue with the mother flue is designated 17. The inner end of the portion 16 merges into a vertical portion 15 which lies along and close to or in contact with the casing 7 and receives into its lower end a neck 45 14 on the top of a box-shaped trap generally designated 12.

The trap 12 is horizontally elongated and its open inner end approaches closely the sides of the fire pot 6, the place where the greatest heat 50 radiation occurs. The trap is placed through a substantially fitting square or other suitable shape of opening in the side wall of the casing 7 where it is secured by attaching means 13.

It will be obvious that the cold air moving down- 55

wardly through the pipe 11 in the manner described and while the furnace is heating up will pass into the lower part of the heating chamber through the trap, but that as soon as the furnace 5 gets hot, the trap 12 will be heated to such an extent that warm air will develop in the trap 12 and the direction of movement of the cold air in the pipe 11 gradually reversed until a column of hot air moves upwardly in the pipe 11 and entering the horizontal portion of the mother flue augments the column of hot air into the mother flue 10 in a manner to increase the volume and heating effect thereof.

A structural assembly of this classification 15 costs little, is much more satisfactory than present arrangements of this character, and economically affords safety and comfort not otherwise obtainable.

A careful consideration of the foregoing description in conjunction with the illustrative drawings will enable the reader to obtain a clear understanding of the purpose, features and advantages, the explicit construction, and the invention as hereinafter claimed.

25 It is to be understood that minor changes in shape, size, relative proportions, and materials may be resorted to in practice without departure from the spirit and scope of the invention as now claimed.

30 I claim:

1. A circulation equalizer for a furnace flue comprising, in combination, a furnace including a fire box, a heated air trapping casing completely surrounding said furnace and spaced therefrom, an air delivery pipe connected to the lower portion of said casing, a heated air conducting flue connected to the top of the casing and extending angularly therefrom, a substantially rectangular additional air trapping box fitted 35 through an opening in the wall of said casing and open at its inner end, said open inner end being located in close spaced proximity to the fire box of said furnace, the opposite end of said box extending through and beyond the opening in 40 said casing and being provided with a heated air discharge nipple, a substantially L-shaped equalizer conduit embodying a vertical branch located on the exterior of and in close proximity to one wall of said casing and connected at its intake 45 end with said nipple, the horizontal branch of said pipe being located in close spaced parallelism to said flue and having communicating connection with said flue at a point remote from said casing.

50 2. In combination, a hot air furnace including a stove member and a casing member surrounding and enclosing said stove member and forming an air heating chamber, said chamber having a cold air intake at its lower end and a heated air outlet 55 at its upper end, a mother flue connected to and fed by said heated air outlet and having a substantially horizontal portion leading away from said furnace, an auxiliary flue having its upper end connected to and communicating with the lower 60 part of one side of said substantially horizontal portion at a point remote from said furnace, the lower end of said auxiliary flue being connected to an intermediate part of one side of said casing member and communicating with the interior of 65 said air heating chamber, said auxiliary flue being arranged to receive naturally descending cold air present in said horizontal portion of the mother flue and convey such descending cold air into said air heating chamber whereby the cold air in said 70 horizontal portion is automatically evacuated 75

therefrom when said stove member is first fired and heated air first starts to move outwardly from said chamber and through said mother flue.

3. In combination, a hot air furnace including a stove member and a casing member surrounding and enclosing said stove member and forming an air heating chamber, said chamber having a cold air intake at its lower end and a heated air outlet 5 at its upper end, a mother flue connected to and fed by said heated air outlet and having a substantially horizontal portion leading away from said furnace, an auxiliary flue having its upper end connected to and communicating with the lower part of one side of said substantially horizontal portion at a point remote from said furnace, the lower end of said auxiliary flue being connected to an intermediate part of one side of said casing member and communicating with the interior of 10 said air heating chamber, said auxiliary flue being arranged to receive naturally descending cold air present in said horizontal portion of the mother flue and convey such descending cold air into said air heating chamber whereby the cold air in said horizontal portion is automatically evacuated 15 therefrom when said stove member is first fired and heated air first starts to move outwardly from said chamber and through said mother flue, said lower end of said auxiliary flue being arranged in 20 heat exchange relation with said stove member whereby additional heated air is produced in said 25 lower end of the auxiliary flue as soon as full firing of the stove member is accomplished, said additional heated air then rising through said auxiliary flue and entering said mother flue so as to 30 augment the heated air therein.

4. In combination, a hot air furnace including a stove member and a casing member surrounding and enclosing said stove member and forming an air heating chamber, said chamber having a cold air intake at its lower end and a heated air outlet 40 at its upper end, a mother flue connected to and fed by said heated air outlet and having a substantially horizontal portion leading away from said furnace, an auxiliary flue having its upper end connected to and communicating with the lower part of one side of said substantially horizontal portion at a point remote from said furnace, the lower end of said auxiliary flue being connected to an intermediate part of one side of said casing member and communicating with the interior of 45 said air heating chamber, said auxiliary flue being arranged to receive naturally descending cold air present in said horizontal portion of the mother flue and convey such descending cold air into said air heating chamber whereby the cold air in said horizontal portion is automatically evacuated 50 therefrom when said stove member is first fired and heated air first starts to move outwardly from said chamber and through said mother flue, said lower end of said auxiliary flue being arranged in 55 heat exchange relation with said stove member whereby additional heated air is produced in said lower end of the auxiliary flue as soon as full firing of the stove member is accomplished, said additional heated air then rising through said auxiliary flue and entering said mother flue so as to 60 augment the heated air therein, said lower end of the auxiliary flue having attached thereto, a trap comprising a box having a portion arranged through an opening in the side wall of said casing member and extending toward said stove member, the radially inward end of said portion of the box being closely spaced from the side of 65 said stove member and open to pass cold air into said chamber against the side of said stove mem- 70

ber and receive heated air from said chamber from the hot side of said stove member.

5. In combination, a hot air furnace including a stove member and a casing member surrounding and enclosing said stove member and forming an air heating chamber, said chamber having a cold air intake at its lower end and a heated air outlet at its upper end, a mother flue connected to and fed by said heated air outlet and having a substantially horizontal portion leading away from said furnace, an auxiliary flue having its upper end connected to and communicating with the lower part of one side of said substantially horizontal portion at a point remote from said 10 furnace, the lower end of said auxiliary flue being connected to an intermediate part of one side of said casing member and communicating with the interior of said air heating chamber, said auxiliary flue being arranged to receive naturally descending cold air present in said horizontal portion of the mother flue and convey such descending cold air into said air heating chamber whereby the cold air in said horizontal portion is automatically evacuated therefrom when said stove member is first fired and heated air first starts to move outwardly from said chamber and through said mother flue, said auxiliary flue having a substantially horizontal part lying along said horizontal portion of the mother flue in heat exchange relation thereto, said auxiliary flue having its upper end connected to and communicating with the lower part of one side of said substantially horizontal portion at a point remote from said furnace, the lower end of said auxiliary flue being connected to an intermediate part of one side of said casing member and communicating with the interior of said air heating chamber, said auxiliary flue being arranged to receive naturally descending cold air present in said horizontal portion of the mother flue and convey such descending cold air into said air heating chamber whereby the cold air in said horizontal portion is automatically evacuated therefrom when said stove member is first fired and heated air first starts to move outwardly from said chamber and through said mother flue, said auxiliary flue having a substantially horizontal part lying along said horizontal portion of the mother flue in heat exchange relation thereto.

30 6. In combination, a hot air furnace including a stove member and a casing member surrounding and enclosing said stove member and forming an air heating chamber, said chamber having a cold air intake at its lower end and a heated air outlet at its upper end, a mother flue connected to and fed by said heated air outlet and having a substantially horizontal portion leading away from said furnace, an auxiliary flue having its upper end connected to and communicating with the lower part of one side of said substantially horizontal portion at a point remote from said furnace, the lower end of said auxiliary flue being connected to an intermediate part of one side of said casing member and communicating with the interior of said air heating chamber, said auxiliary flue being arranged to receive naturally descending cold air present in said horizontal portion of the mother flue and convey such descending cold air into said air heating chamber whereby the cold air in said horizontal portion is automatically evacuated therefrom when said stove member is first fired and heated air first starts to move outwardly from said chamber and through said mother flue, said auxiliary flue having a substantially horizontal part lying along said horizontal portion of the mother flue in heat exchange relation thereto, said auxiliary flue being arranged exteriorly of said mother flue.

60 7. In combination, a hot air furnace including a stove member and a casing member surrounding and enclosing said stove member and forming an air heating chamber, said chamber having a cold air intake at its lower end and a heated air outlet at its upper end, a mother flue connected to and fed by said heated air outlet and having a substantially horizontal portion leading away from said furnace, an auxiliary flue having its upper end connected to and communicating with the lower part of one side of said substantially horizontal portion at a point remote from said furnace, the lower end of said auxiliary flue being connected to an intermediate part of one side of said casing member and communicating with the interior of said air heating chamber, said aux-

iliary flue being arranged to receive naturally descending cold air present in said horizontal portion of the mother flue and convey such descending cold air into said air heating chamber whereby the cold air in said horizontal portion is automatically evacuated therefrom when said stove member is first fired and heated air first starts to move outwardly from said chamber and through said mother flue, said auxiliary flue having a substantially horizontal part lying along said horizontal portion of the mother flue in heat exchange relation thereto, said auxiliary flue having a vertical portion arranged exterior of and in heat exchange relation to the side wall of said casing member.

15 8. In combination, a hot air furnace including a stove member and a casing member surrounding and enclosing said stove member and forming an air heating chamber, said chamber having a cold air intake at its lower end and a heated air outlet at its upper end, a mother flue connected to and fed by said heated air outlet and having a substantially horizontal portion leading away from said furnace, an auxiliary flue having its upper end connected to and communicating with the lower part of one side of said substantially horizontal portion at a point remote from said furnace, the lower end of said auxiliary flue being connected to an intermediate part of one side of said casing member and communicating with the interior of said air heating chamber, said auxiliary flue being arranged to receive naturally descending cold air present in said horizontal portion of the mother flue and convey such descending cold air into said air heating chamber whereby the cold air in said horizontal portion is automatically evacuated therefrom when said stove member is first fired and heated air first starts to move outwardly from said chamber and through said mother flue, said lower end of said auxiliary flue being arranged in heat exchange relation with said stove member whereby additional heated air is produced in said lower end of the auxiliary flue as soon as full firing of the stove member is accomplished, said additional heated air then rising through said auxiliary flue and entering said mother flue so as to augment the heated air therein, said lower end of the auxiliary flue having attached thereto, a trap comprising a box having a portion arranged through an opening in the side wall of said casing member and extending toward said stove member, the radially inward end of said portion of the box being closely spaced from the side of said stove member and open to pass cold air into said chamber against the side of said stove member and receive heated air from said chamber from the hot side of said stove member, said lower end of the auxiliary flue entering the top of a portion of said box which extends outwardly of said casing member.

35 9. A hot air furnace including a stove spacedly enclosed by a casing defining an air heating chamber, said chamber having an unheated air inlet in its lower part and a heated air outlet in its upper part to which outlet a main heated air flue is connected and leads away from said furnace to deliver heated air to an enclosure to be heated, means connected between an outward part of said main flue and leading downwardly and connected to a lower part of said casing and communicating with the interior of said chamber and having a portion close to and in heat exchange relation to said stove, said means being arranged to receive naturally descending cold air

present in said main flue and convey the same into said lower part of said chamber while the stove is first being fired and heated air starts outwardly in said main flue, said portion of said means which is in heat exchange relation to said stove being arranged to be heated by said stove

as the stove becomes hot whereby heated air will be caused to rise and be conveyed by said means to said main flue to augment the heated air in said main flue.

JAMES Z. ANDERSON.
